POWER UNIT FOR A WELL PIPE SLIP ASSEMBLY

Gird E. Mullinix, South Gate, Calif., assignor to
Byron Jackson Co., Los Angeles, Calif., a corporation of Delaware

Application January 14, 1950, Serial No. 138,589

8 Claims. (Cl. 254—93)

1

This invention relates to the well drilling art and is directed to improvements in well pipe supporting apparatus. This invention finds particular usefulness in connection with power units for raising and lowering pipe slip assemblies with respect to a slip bowl.

In the well drilling art it is common to employ a drill string for rotating a bit, the drill string being formed of a plurality of pipe sections joined end-to-end by threaded connections. The bit becomes dull and must be withdrawn at intervals from the bore hole for replacement. The threaded joints between the pipe sections are customarily connected by supporting the lower portion of the pipe string by means of a plurality of wedge-shaped slips which are received within a stationary slip bowl. An upper section of pipe is then connected by turning it with respect to the lower portion of the drill string. The slips and slip bowl are also employed for supporting and rotating the lower portion of the drill string when the pipe joints are to be disconnected.

Although such slip assemblies are ordinarily moved by hand to and from operative position within the slip bowl, power operated devices have been used with some success for performing this operation. The use of power eliminates the necessity of repeatedly lifting the slip assembly out of the slip bowl by hand. Fatigue of the crew members operating such assembly is thereby greatly reduced, and the crew members remain more alert to possible danger in the operation of the rig equipment.

One of the objects of my invention is to provide a power unit for use in raising and lowering pipe supporting slip assemblies, the power unit employing novel means for lifting and guiding a tubular post or column which carries the off-center weight of the slip assembly by means of a laterally extending arm secured to its upper end.

Another object is to provide a power lift device of this type having novel construction so that a minimum over-all height is achieved.

Another object is to provide a lift device of this type which is effective both for raising and for lowering the slip assembly under power.

Another object is to provide a power operated lift device for a well pipe slip assembly which includes a lift column pivotally supported so that it may swing the slip assembly and carrier arm laterally to an inoperative position on the derrick floor.

A related object is to provide a device of 55 No. 138,588, filed January 14, 1950. Another type

this type having a novel form of rotation latch device.

Another object is to provide a tubular post or lift column which is subject to bending forces applied by the weight of the lateral arm and slip assembly, and in which the outer surface of the column is used for guiding the column for axial movement, and wherein the inner bore of the column is employed in connection with the stationary piston for moving the column by fluid pressure.

A further object of this invention is to provide a novel form of connection for securing the laterally extending arm to the upper end of the lift column.

Other objects and advantages will appear more fully hereinafter.

In the drawings:

Figure 1 is a side elevation partly broken away showing a rotary machine, a pipe slip supporting assembly, and a power unit for actuating said assembly, the power unit comprising a preferred embodiment of my invention.

Figure 2 is a top plan view thereof partly broken away.

Figure 3 is a sectional elevation of the power unit taken substantially on the lines 3—3 as shown in Figure 2.

Figure 4 is a sectional plan view taken substantially on the lines 4—4 as shown in Figure 3.

Figure 5 is a sectional plan view taken substantially on the lines 5—5 as shown in Figure 3.

Figure 6 is a sectional plan view taken on the lines 6—6 as shown in Figure 3.

Figure 7 is a sectional elevation partly broken away taken substantially on the lines 7—7 as shown in Figure 5.

Figure 8 is a fragmentary sectional plan view showing the head member in tilted position with respect to the lift column.

Referring to the drawings, the power unit generally designated 10 comprises in general an upright frame 11 from which a vertical lifting post or column 12 projects. The post 12 is guided for reciprocation within the frame and carries a head member 13 at its upper projecting end. Laterally projecting arm 14 connects the head 13 to a support structure 15 which carries a unitary slip assembly 16. The slip assembly 16 is movable into operative position within the slip bowl 17 provided on the master bushing 18 of the rotary machine 19. A preferred type of slip assembly 16 and support structure 15 is shown and described in my copending application, Serial

of slip assembly and support structure is shown in my copending application, Serial No. 660,679, filed April 9, 1946, now issued as Patent No. 2,575,356, dated November 20, 1950.

The function of the power unit 10 is to raise and lower the support structure 15 and slip assembly 16 in order to "set" the slips for supporting a well pipe 20.

The rotary machine 19 may be of any standard design and rests upon the usual supporting structure (not shown). A mounting flange 21 is provided on the base of the rotary machine 19 and supports a mating flange 22 by means of bolts 23. The mating flange carries a sub-base 24 which in turn supports the upright frame 18 and is connected thereto by means of bolts 25.

As shown in Figures 3-7, the tubular column or lifting post 12 comprises a cylindrical member closed at its upper end and mounted for vertical reciprocation within the frame 11. The post 12 is relatively large in diameter in order to withstand without undue deflection the off-center or side load imposed by the weight of the supporting structure 15 and unitized slip assembly 16. The post is guided on its outer periphery by roller elements carried on the frame and is raised and lowered by fluid pressure acting within its internal bore 26. An axially immovable piston rod assembly 27 extends upwardly into the bore 26 and carries a piston 28 at its upper end which forms a sliding seal within the bore 28. The piston 28 divides the bore 26 into an upper pressure chamber 29 and a lower pressure chamber 30. The piston assembly 27 comprises a pair of concentric tubes 31 and 32 which cooperate to define an inner fluid passageway 33 and an annular fluid passageway 34. The outer tube 32 is provided with an annular shoulder 35 which rests on the thrust bearing assembly 36. This assembly 36 is carried on the base plate 37 which is attached to the frame 11 by means of bolted connections 38. The lower end of the outer tube 32 extends downwardly through the bore 42 in the base plate 37 so that it may rotate relative to base plate 37. A snap ring 49 on the lower projecting end of the outer tube 32 maintains the parts in assembled relation.

The inner tube 31 is enlarged at each end to fit within the bore of the outer tube 32 and to form a seal therewith. The annular passageway 34 communicates with a port 39 in the outer tube 32 to establish communication with the lower pressure chamber 30. The annular passageway 34 also communicates with lateral ports 40 formed in the wall of the outer tube 32 and with an annular recess 41 provided in the wall of the central bore 42 of the base plate 37. A passage 43 in the base plate 37 communicates with the annular recess 41 and with suitable piping connections 44. Similarly, the inner passageway 33 communicates through ports 45 in the wall of the outer tube 32 with an annular recess 46 formed adjacent the bore 42 in the base plate 37. The passage 47 in the base plate 37 communicates between the annular recess 46 and the piping 48. From this description it will be understood that the piping 48 communicates via the passage 47 and inner passageway 33 with the upper pressure chamber 29, while the piping 44 communicates via passage 43 and annular passageway 34 to the lower pressure chamber 30.

The lower end of the lower pressure chamber 30 is defined by a cylinder head 50 which is received within the lower end of the tubular post 12 and held in position against an annular shoul-

der 51 by means of a snap ring 52. The cylinder head 50 is provided with a central bore 53 for a sliding reception of the outer surface of the outer tube 32 on the piston rod assembly 27. An outer sealing ring 54 prevents leakage of fluid between the cylinder head 50 and the tubular post 12, and an inner sealing ring 55 prevents leakage between the cylinder head 50 and the outer surface of the outer tube 32.

10 A four-way control valve 56 is provided at a convenient elevation and connected by suitable piping to the line 44 and 48, as well as to a vent and a pressure supply source (not shown). When the four-way valve 56 is turned to one position 15 fluid pressure is admitted to the upper pressure chamber 29 and exhausted from the low pressure chamber 30 so that the post 12 is raised. When the four-way valve 56 is turned to another position 20 the fluid pressure is admitted into the lower pressure chamber 30 and exhausted from the upper pressure chamber 29 so that the post 12 is moved downwardly under power.

Suitable guide means are provided for guiding the post 12 with respect to the frame 11. As 25 shown in the drawings, this means includes three guide roller assemblies 60, 61 and 62 mounted within the upper portion of the frame or housing 11 and a pair of rollers 63 mounted upon trunnions 64 provided on the ring generally designated 65. The ring 65 is carried on the lower end of the plunger and the rollers 63 are disposed within vertical trackways 66 provided on opposite sides of the frame 11. The three 30 guide roller assemblies 60, 61 and 62 are mounted on a support plate 67 which is in turn secured to a flange 68 of the frame 11 as by stud bolts 69 (see Figure 7). As shown particularly in Figure 5, the plate 67 is generally U-shaped in plan view and the three guide roller assemblies are disposed thereon and substantially equally spaced about the post 12. The front or main guide roller assembly 60 comprises two vertically spaced rollers 70 carried upon shafts 71 supported within a bifurcated bracket element 72. A bore 73 is formed in the bracket element 72 to receive 40 a supporting shaft 74, the ends of said shaft being secured within spaced lugs 75 formed at opposite sides of the open end of the support plate 67. The other two guide roller assemblies 61 and 62 are substantially identical to one another, each including a single roller 76 carried by shafts 77 and 78 respectively. The ends of these shafts are supported within upstanding spaced lugs 79 on the plate 67. All four rollers 45 are substantially identical and are provided with friction-reducing needle-type bearings 80. It will be noted that the face of each roller is contoured to conform to the outer cylindrical surface of the tubular post 12, whereby a maximum bearing surface will be presented by said rollers to the surface of said post. The main guide roller assembly 60 is preferably provided with two rollers as shown, rather than a single roller, inasmuch as said main assembly is subjected to considerably greater lateral force from the post 12 than either of the other guide roller assemblies 61 and 62, especially at such time as the slip assembly 16 is being raised from the master bushing bowl 17.

As shown in Figure 7, the support plate 67 includes an integral depending threaded boss 81 carrying a downwardly extending stop bolt 82. This bolt is provided with a lock nut 83. The function of this stop bolt 82 is to limit the upward stroke of the post 12. A resilient bumper

element 84 is secured to the trunnion ring 65, which bumper element is adapted to engage the head of said stop bolt.

The trunnion ring or guide ring 65 is rotatably carried by the lower end of the post 12 by means of the ball bearing assembly 85. As shown in Figure 6, access is provided to the bearing raceway 86 by means of a removable plug 87, and the individual balls 88 of the bearing assembly 85 are introduced into the raceway 86 through the opening normally closed by the plug 87. A fitting 89 is provided at one side of the ring 65 whereby lubricant may be supplied to said bearing assembly. A pair of O-rings 90 disposed in annular grooves formed in the guide ring 65 on either side of the bearing assembly 85 retain lubricant supplied through fitting 89 and also to prevent the entrance of foreign matter. The rollers 63 turn upon roller bearing assemblies 91 provided upon the integral trunnions 64 carried on the ring 65.

The trunnions are axially bored at 93 whereby a part of the lubricant supplied through fitting 89 may reach the bearings 91 of the two rollers 63. End covers 94 direct lubricant into the bearings 91. The vertical trackways 66 are defined by two pairs of ribs 95, which pairs of ribs constitute integral inward extensions of the inner wall of the frame 11. It will be noted that the rollers 63 each include a flange 96 adapted to abut the inner surfaces 97 of the ribs so as to prevent more than a slight amount of lateral movement of the bottom of the post 12 in a direction toward either pair of ribs 95.

The post 12 must normally be locked against rotation with respect to frame 11 in order that the slip assembly 16 will remain in substantial vertical alignment with the master bushing bowl 17. For this purpose the guide ring 65 is provided with a pair of spaced lugs 98 adapted to support the ends of a shaft 99 upon which is pivotally mounted a latch 100. The upper portion of this latch 100 includes a tongue 101 which is normally disposed between a pair of spaced lugs 102 formed on a latch ring 103, which latch ring is rigidly secured to the post 12, as by welding, just above the guide ring 65. A torsion spring 104 carried by shaft 99 serves to constantly exert an inward or closing force upon the latch 100. To release said latch whereby the post will be free to turn with respect to the frame, the post is moved upwardly so as to dispose the latch 100 adjacent a hinged door 105 formed at the rear of the frame 11. The door 105 is then opened to permit a crew member to reach into the frame and pull the upper part of the latch 100 outwardly whereby the tongue 101 will be displaced from between the lugs 102 and the post will be free to rotate. When unlatched, the tongue 101 will ride upon the outer periphery of the latch ring 103. At such time as the post 12 is turned back to its normal position said tongue will automatically snap back into latched position under the influence of the spring 104.

The piston 28 is free to rotate in unison with the post 12 by virtue of the rotatable connection of the piston rod assembly 27 to the housing base plate 31. Hence, the lower packing ring 106 of said piston, when expanded by the fluid pressure within the lower pressure chamber 30, will not restrain rotation of the post 12. It will be seen that the aforescribed construction makes it possible to move the slip assembly 16 into an inoperative position clear of the rotary machine 19 when not in use by rotating the slip assembly sup-

port structure 15 about the vertical axis of the post 12.

As shown in the drawings, the frame 11 does not comprise a single integral member but rather comprises a main body 110 having a footing 121, a detachable access panel 111 secured to said main body as by bolts 112 and having the hinged door 105 mounted thereon, and a top cover 113. The top cover 113 is shown secured to the support plate 67 by removable cap screws 114. These various components of the frame 11 cooperate to form an enclosure 115. The bottom rear portion of the frame may be left open as at 116 to provide easy access to the enclosure 115. The door 105 on the access panel 111 may be pivotally mounted upon an inclined hinge structure 107 so that said door automatically shuts by gravity. With particular regard to the top cover 113, it will be seen that a resilient wiper element 117 is secured centrally thereto to prevent the entrance of foreign matter into the frame enclosure 115.

The head member 13 interconnects the upper end of the post 12 and the end of the laterally extending support arm 14. The head member 13 comprises, generally, a platform element 118 rigidly secured, as by welding, to the upper end of the tubular post 12, and serves to close the upper end of the bore 26 in the post. A mounting cap 119 is pivotally supported upon said platform element 118 by means of a horizontal pivot bolt 120 and is provided with a mounting flange 122 to which the end of the laterally extending arm 14 is adapted to be rigidly secured as by bolts 123. A horizontally slidable latch member 124 cooperates with a pivoted link 125, as described in detail hereinafter, to releasably latch the mounting cap 119 against pivotal movement relative to the platform element 118 about the axis of pivot bolt 120.

The front portion of the platform element includes an internally threaded boss 126 which receives a downwardly extending stop bolt 127. This bolt 127 is vertically adjustable with respect to the platform element and is provided with a lock nut 128. The function of this stop bolt is to limit the downward travel of post 12 by the engagement of the bolt head with a resilient bumper element 129 secured to the top of the frame 11.

An upstanding spring mount 130 is also formed at the front portion of platform element 118. The platform element 118 is formed at its midportion with a pair of upstanding spaced lugs 131 which support shaft bolt 120. The platform element is formed at its rear portion with a pair of laterally extending spaced lugs 132 which are adapted to receive the ends of a link shaft 133. The mounting cap 119 is of generally circular configuration in plan view except for the elongated mounting flange 122 for arm 14. Said cap includes a pair of shaft bolt lugs 134 bored to receive shaft bolt 120. A pair of laterally extending spaced lugs 135 are formed upon the rear side walls of the cap and are bored for the reception of the ends of a shear pin 136.

The link 125 pivotally receives the central portion of the shear pin 136. An elongate bore 137 formed at the front portion of said link accommodates the center portion of the link shaft 133. It will be noted that the upper front portions of link 125 include a pair of lateral extensions 138 which overlie and rest upon the pads 150 provided upon the platform element 118. Accordingly, counterclockwise pivotal movement of the mounting cap 119 about the axis of shaft bolt 120 is normally prevented, inasmuch as such movement

is resisted by the shear pin 136. It should be noted that the shear pin 136 is purposely made relatively small and of insufficient strength to withstand a severe shock or blow, so that in the event the arm 14 of the slip assembly support structure 15 is inadvertently subjected to an excessive load in either upward or downward direction, said shear pin 136 will fail and allow the mounting cap 119 to pivot clockwise or counter-clockwise about the axis of shaft bolt 120.

The latch member 124 is disposed between the upstanding lugs 131 of platform element 118 and includes a latch lug 139 at its rear portion and a spring chamber 140 at its front portion. An elongated slot 141 formed in said latch 124 accommodates the center portion of the shaft bolt 120 whereby horizontal movement of said latch 124 toward or away from the link 125 is permitted, said latch being adapted to slide upon the flat surfaces 142 formed upon the platform element 118. A compression spring 143 disposed between the spring mount 130 of the platform element and the end wall of the spring chamber 140 serves to constantly urge the latch 124 toward the link 125. As shown in Figures 3 and 4, the top surface 144 of the upper front portion of said link 125 normally abuts the underside of the latch lug 139 on the latch 124. Accordingly, the mounting cap 119 is normally restrained against clockwise pivotal movement about the axis of shaft bolt 120. However, it is possible to release the front portion of said link 125 from engagement with the latch lug 139 by moving the latch 124 in a direction away from said link 125. This is accomplished by inserting a suitable tool (not shown) through an aperture 145 formed in the rear side wall of the mounting cap 119 so as to engage the end surface of the latch lug and force the latch 124 toward the front portion of the mounting cap 119. It is then possible to pivot the mounting cap clockwise about shaft bolt 120 inasmuch as said link 125 will then be free to swing about the shaft 133, as shown in Figure 8. As soon as the front portion of the link 125 has been raised a short distance the latch 124 may be released, inasmuch as the forward end 146 of the link will then abut the rear end surface 147 of the latch lug 139. As the front of the mounting cap 119 continues to rise, the link 125 becomes disengaged from the latch 124. At this time the head member elements will assume the position shown in Figure 8, the spring 143 having returned latch 124 to its normal position.

When the mounting cap 119 is pivoted counter-clockwise to lower the arm 14, the front of the link 125 will also gradually be lowered until the forward end surface 146 thereof engages the rear end surface 147 of the latch lug 139. Thereafter, as the result of this engagement the latch 124 will be cammed toward the front portion of the cap 119 against the resistance of spring 143 until such time as the top surface 144 of said link assumes a lower elevation than the bottom surface 149 of said latch lug, whereupon the latch will automatically snap back into its normal position.

It should be understood that this construction makes it possible to raise the slip assembly 16 and its support structure 15 with respect to the post 12. This feature may prove very desirable at such time as the slip assembly 16 is to be moved to an inoperative position clear of the rotary machine 19. It will also be understood that the normal procedure in so moving the slip assembly involves raising the post 12 so as to dispose the latch 100 adjacent the housing door 105, releasing

7
8
said latch 100, then swinging the arm 14 and slip assembly 16 about the axis of the post 12 to a point preferably directly behind the frame 11. It occasionally happens, however, that certain drilling apparatus or equipment will be disposed upon the derrick floor on the arc path to be traversed by the slip assembly, said equipment being of such a height as to interfere with the movement of said slip assembly. In this situation the latch 124 within head 13 may be disengaged so as to release mounting cap 119 for pivotal movement about the bolt 120 whereby a catline (not shown) may be attached to the slip assembly support structure 15 so as to raise it clear of the obstruction while being moved to its out-of-the-way position.

The embodiment of the invention just described is universally adaptable to the various makes and sizes of rotary machines because of the provision of the vertically adjustable stop bolts 82 and 127, these bolts making it possible to limit the stroke of the post 12 whereby the slip assembly 16 will seat at exactly the correct depth within the master bushing bowl 17. The guide means provided for the post 12 prevent wobble of the post with respect to the frame 11 even at such time as said post reaches the top of its stroke. The mounting of the head member 13 for pivotal movement about the horizontal bolt 120 and pivotal movement about the vertical axis of the post 12 provides a simple arrangement for moving the slip assembly 16 and its support structure 15 into an inoperative storage position wholly clear of the rotary machine 19.

Having fully described my invention, it is to be understood that I do not wish to be limited to the details herein set forth, but my invention is of the full scope of the appended claims.

I claim:

1. In a power unit for lifting a lateral support arm carrying a well pipe slip assembly, the combination of: a stationary frame, an upright post, guide rollers carried on the upper portion of the frame engaging the post, a trunnion ring rotatably mounted on the lower end of the post and having laterally extending trunnions, rollers on the trunnions guided by vertical trackways on the frame, the upper end of the post extending above the frame, attachment parts on said upper end of the post for securing the lateral support arm thereto, and cooperating fluid operated elements for raising the post relative to the frame.

2. In a power unit for lifting a lateral support arm carrying a well pipe slip assembly, the combination of: a stationary frame, an upright post, guide rollers carried on the upper portion of the frame engaging the post, a trunnion ring rotatably mounted on the lower end of the post and having laterally extending trunnions, rollers on the trunnions guided by vertical trackways on the frame, releasable latch parts for preventing relative rotation between the trunnion ring and the post, the upper end of the post extending above the frame, attachment parts on said upper end of the post for securing the lateral support arm thereto, and cooperating fluid-operated elements for raising the post relative to the frame.

3. In a power unit for lifting a lateral support arm carrying a well pipe slip assembly, the combination of: a stationary frame, an upright tubular post, guide rollers carried on the upper portion of the frame engaging the post, a trunnion ring rotatably mounted on the lower end of the post and having laterally extending trunnions, rollers on the trunnions guided by verti-

cal trackways on the frame, the upper end of the post extending above the frame, attachment parts on said upper end of the post for securing the lateral support arm thereto, an axially immovable piston rod turnably mounted on the 5 base and extending into the interior of the post from the lower end thereof, a piston fixed on the piston rod and slidably engaging the interior surface of the tubular post to form a seal, the piston rod having a conduit for admitting fluid 10 pressure into the interior of the tubular post above the piston for raising the post relative to the frame.

4. In a power unit for lifting a lateral support arm carrying a well pipe slip assembly, the combination of: a stationary frame, an upright tubular post, guide rollers carried on the upper portion of the frame engaging the post, a trunnion ring rotatably mounted on the lower end of the post and having laterally extending trunnions, 15 cooperating latch parts for releasably latching the trunnion ring and post against relative rotation, rollers on the trunnions guided by vertical trackways on the frame, the upper end of the post extending above the frame, attachment parts on said upper end of the post for securing the lateral support arm thereto, an axially immovable piston rod extending into the interior of the post from the lower end thereof, a thrust bearing rotatably supporting the piston rod upon 20 the frame, and a piston fixed on the piston rod and slidably engaging the interior surface of the tubular post to form a seal.

5. A power unit adapted to provide vertical reciprocal movement of a well pipe slip assembly support structure, comprising: a stationary frame, a post disposed within said frame for vertical reciprocal movement with respect thereto, guide means disposed between said frame and said post to guide said post for vertical movement with respect to said frame, releasable latch means normally interlocking said frame and said post whereby said post is normally restrained against rotation with respect to said frame but is adaptable upon release of said latch means to be rotated about its vertical axis, a head member carried by said post and attachable to said slip assembly support structure, and horizontal pivot means mounting said head member on said post for pivotal swinging movement relative thereto. 45

6. A power unit adapted to provide vertical reciprocal movement of a well pipe slip assembly support structure, comprising: a stationary frame, a post disposed within said frame for vertical reciprocal movement with respect thereto, 50 guide means disposed between said frame and said post to guide said post for vertical move-

ment with respect to said frame, releasable latch means normally interlocking said frame and said post whereby said post is normally restrained against rotation with respect to said frame but is adaptable upon release of said latch means to be rotated about its vertical axis, a head member carried by said post and attachable to said slip assembly support structure, horizontal pivot means mounting said head member on said post for pivotal swinging movement relative thereto, and means releasably latching said head member against pivotal swinging movement relative to said post.

7. In a power unit for lifting a well pipe slip assembly, the combination of: a stationary frame, a post guided for vertical movement on the frame, a platform member fixed on the upper end of the post, a tiltable member having a laterally extending support arm secured thereto, a horizontal pivot shaft pivotally connecting said members, releasable means for preventing relative pivotal movement between said members under normal operating conditions, said means including a frangible element proportioned to fail in the event that overload stresses should be applied to the support arm.

8. In a power unit for lifting a well pipe slip assembly, the combination of: a stationary frame, a post guided for vertical movement on the frame, a platform member fixed on the upper end of the post, a tiltable member having a laterally extending support arm secured thereto, a horizontal pivot shaft pivotally connecting said members, releasable means for preventing relative pivotal movement between said members under normal operating conditions, said means including a link pivotally connected to each of said members at spaced locations, a portion of the link engaging one of the members so that relative pivotal movement between the members in one direction is prevented, and a latch on the other member releasably engaging the link so that relative pivotal movement between the members in the other direction is also prevented.

GIRD E. MULLINIX.
